DESIGN FOR A COMBINED FAUCET AND SOAP HOLDER

Charles B. Mortimer, Lakewood, Ohio, assignor to The Central Brass Manufacturing Company,
Cleveland, Ohio, a corporation of Ohio

Application September 20, 1939, Serial No. 87,310

Term of patent 7 years

To all whom it may concern:

Be it known that I, Charles B. Mortimer, a citizen of the United States, residing at Lakewood, in the county of Cuyahoga and State of Ohio, have invented a new, original, and ornamental Design for a Combined Faucet and Soap Holder, of which the following is a specification, reference being had to the accompanying drawing, forming part thereof.

In the drawing, Fig. 1 is a front elevation; Fig. 2 is a top plan view; and Fig. 3 is an end elevational view showing my new design of a combined faucet and soap holder.

I claim:

The ornamental design for a combined faucet and soap holder, as shown.

CHARLES B. MORTIMER.
